UNITED STATES PATENT OFFICE

JOHN E. LANDOLT, OF TOLEDO, OHIO, ASSIGNOR TO LIBBEY-OWENS-FORD GLASS COMPANY, OF TOLEDO, OHIO, A CORPORATION OF OHIO

SHEET-GLASS-SURFACING APPARATUS

Application filed June 25, 1927. Serial No. 201,343.

The present invention relates to sheet glass surfacing apparatus.

An important object of the invention is to provide in sheet glass surfacing apparatus, means for supplying polishing medium to the sheet or sheets of glass to be surfaced.

A further object of the invention is to provide in sheet glass surfacing apparatus, a polishing mechanism including preferably means for supporting a sheet or sheets of glass and rotating the same during the polishing operation, polishing members adapted to contact with said sheet, and means for discharging a fluid upon the sheet, and for instantaneously cutting off said discharge when desired.

Another object is to provide in sheet glass surfacing apparatus and particularly a polishing machine, a plurality of conduits associated with a single header, which in turn is connected to a suitable source of liquid supply, said conduits being inclined downwardly toward the header so that when the fluid is turned off the pipes will drain back through said header.

Other objects and advantages of the invention will become more apparent during the course of the following description when taken in connection with the accompanying drawings.

In the drawings wherein like numerals are employed to designate like parts throughout the same,

Fig. 1 is an elevation of a form of surfacing machine illustrating my invention in use, and

Fig. 2 is a plan view thereof, illustrating diagrammatically the arrangement of conduits used.

Although the invention is not necessarily restricted for use in connection with any particular type of glass surfacing machine, it has been designed primarily for that type of machine where the sheet or sheets of glass are supported upon a rotating table in a manner that surfacing elements may rest upon said sheet of glass and caused to rotate by reason of frictional contact therewith.

In the drawings, the numeral 5 designates a polishing machine in its entirety which com-

prises a frame 6, a rotatable table 7 adapted to support the sheet of glass 8 to be surfaced, and a plurality of surfacing units 9. In the drawings the surfacing elements are in the form of polishing members which may be 55 belt covered blocks 10.

In the production of plate glass, the glass blank is usually first ground by means of suitable abrasive or abrasives, after which it is subjected to a polishing action. The polishing is usually accomplished by means of a rouge mixture and hot water. In using the machine illustrated, a rouge mixture is usually applied fairly heavy at the beginning of the operation, after which the supply of rouge 60 is tapered off and hot water is supplied.

To insure that the supply of hot water be cut off instantly when it is desired to no longer furnish the same, I have provided a construction wherein the excess water remaining in 70 the conduits is discharged away from the sheet.

In the drawings the numeral 11 designates a polishing medium supply pipe. As above stated, the polishing medium is usually rouge 75 mixed with water. Connected to the conduit 11 and associated with the machine is a pipe 12. The pipe 12 is adapted to discharge the polishing medium through the end 13 upon the sheet, while a valve 14 controlled by 80 means of the handle 15 is used to control the amount of rouge fed.

A pipe 16 is provided and has preferably hot water or similar fluid circulating therethrough. A header 17 is mounted on the 85 machine and has a plurality of pipes 18 extending therefrom. The header is connected by means of the pipe 19 to the conduit 16, a valve 20 being arranged in said line 19 to control the flow to the header. A valve 21 is also 90 arranged in each one of the lines 18.

A discharge pipe 22 and valve 23 is connected to the header 17 as shown. The header 17 is slanted downwardly toward the discharge pipe 22, while the pipes 18 are in turn 95 inclined toward the header, except of course for the discharge ends 24. A supplementary pipe 25 is also connected to the header and to the rouge line 11, the pipe 25 being controlled by means of the valve 26.

In normal operation, when the sheet 8 is first placed upon the table to be polished, the valve 20 is closed and the valve 23 is open. The valve 14 is then opened by means of the operating handle 15 so that rouge will be discharged upon the sheet. At some time during the operation it may be desirable to add a little hot water, and to do this the valve 23 is closed and the valve 20 is opened to the desired extent. By controlling the individual valves 21, the discharge of hot water can be accurately controlled. When it is desired to stop using the water, the valve 20 is closed and the valve 23 is opened. Immediately, due to the inclination of the header and the associated pipes, the excess water will flow through the discharge pipe 22 into a gutter which is positioned beneath the table, but which is not illustrated for the purpose of clearness.

In some instances, it may be desirable to discharge polishing medium through the pipes 24, in which case the valve 26 may be opened which will permit the rouge to flow from the pipe 11 through the pipes 24.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

Claims:

1. In sheet glass surfacing apparatus, means for supplying polishing medium to the sheet of glass to be surfaced, said means comprising a main conduit containing a polishing medium, an inclined header, means connecting the main conduit and header, a valve in said connecting means for controlling the supply of polishing medium to the sheet of glass to be surfaced, a plurality of pipes connected to the header and inclining upwardly away therefrom, and a valve controlled drain pipe connected to the lower end of said header adapted to drain the plurality of pipes and the inclined header when the valve in said main conduit and header connecting means is closed.

2. In apparatus for supplying a polishing medium to a glass sheet to be surfaced, a plurality of fixed conduits terminating in discharge spouts positioned above the glass sheet, means for supplying a polishing medium to the conduits whereby it is discharged from said spouts onto said sheet, said conduits inclining downwardly away from the discharge spouts, and a common drain pipe connected with the lower ends of said conduits remote from said spouts for draining the conduits when the supply of polishing medium thereto is shut off.

3. In apparatus for supplying a polishing medium to a glass sheet to be surfaced, an in-

clined header, a plurality of pipes connected thereto and inclining upwardly away therefrom, said pipes terminating in discharge nozzles positioned above the sheet, means for supplying a polishing medium to the header and pipes whereby the same is discharged from said nozzles onto said sheet, and a drain pipe connected to the lower end of said header for draining said header and pipes when the supply of polishing medium thereto is shut off.

4. In apparatus for supplying a polishing medium to a glass sheet to be surfaced, a main conduit adapted to contain the polishing medium, an inclined header, a connection between the main conduit and header, a valve in said connection for controlling the supply of polishing medium to said header, a second main conduit adapted to contain water, a connection between the second conduit and header, a valve in said last named connection for controlling the supply of water to said header, a plurality of pipes connected to said header and inclining upwardly away therefrom, said pipes terminating in discharge nozzles positioned above the glass sheet to be surfaced for discharging the polishing medium and water thereupon, and a valve controlled drain pipe connected to the lower end of said header for draining the header and pipes when the valves in the connections between the header and main conduits are closed.

Signed at Toledo, in the county of Lucas and State of Ohio, this 23rd day of June, 1927.

JOHN E. LANDOLT.
